WILLIAM H. SCHAEFFER, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

VOLUME CONTROL

Application filed April 4, 1931. Serial No. 527,639.

My invention relates to the control of volume of reproduction, particularly of radio receiving apparatus, and particularly to the prevention of electrical interaction between the components of a multiple volume control unit.

In accordance with my invention, adjustable impedances, particularly resistances, in different circuits of tube, specifically a radio frequency amplifier, are disposed adjacent each other, as in a common housing, for concurrent adjustment by the same operating member or shaft, and to prevent noises in the loud speaker, or equivalent, by movement of the control contacts of the impedances, a plate of conductive material is disposed between the impedances and preferably connected to a point at ground potential.

My invention also resides in the features of construction, arrangement and combination hereinafter described and claimed.

For an understanding of my invention and for illustration of the several forms it may take, reference is to be had to the accompanying drawings, in which:

Fig. 1 illustrates diagrammatically radio receiving apparatus utilizing the invention.

Fig. 2 is an elevational view in section, of a multiple volume control unit utilized in the system of Fig. 1.

Fig. 3 illustrates diagrammatically a further circuit arrangement utilizing my invention.

Fig. 4 is an elevational view in section of a modified form of a multiple volume control unit utilized in the system of Fig. 3.

Fig. 5 illustrates diagrammatically a further circuit arrangement utilizing my invention.

Referring to Fig. 1, radio frequency signal energy impressed upon the input circuit of tube V, as by an antenna system, not shown, or by a selective system interposed between the tube and an antenna, or a preceding amplifier, is amplified and impressed upon the tunable input circuit T1, C1 of amplifier tube V1 which further amplifies the signal energy and impresses it upon the input circuit of a

detector D directly, or indirectly, through another amplifier stage including the tube

V2 and its input circuit T2, C2. The output of the detector is fed to a loud speaker LS, preferably after amplification by the audio frequency amplifier A.

Along the resistance R of suitably high magnitude, which shunts the primary turns P1 of coil T1, is adjustable a contact S for controlling the volume of reproduction by varying the effective signal voltage impressed upon the grid g1 of amplifier V1. The control contact, as indicated, may be connected to the anode α of the tube V through a condenser K which is of low impedance to radio frequency currents as are also condensers K1, K2.

The adjustable resistance R1 and fixed resistance R2 in series, are traversed by direct current derived from a suitable direct-current source, as batteries, or a rectifier-filter system. The screen grids s of the tubes V1 and V2 are connected to adjustable contact S1 of resistance R1, and the cathodes f of the same tubes are connected to a suitable point along resistance R2. As the contact S1 is moved along resistance R1, the difference of potential between the screen grids s and the cathodes f of the tubes is varied to change the amplification characteristic of the tubes and thus modify the amplitude of reproduction by the loud speaker LS.

The volume control contacts S and S1 are mechanically coupled as generically indicated by the dash line α , for adjustment in unison by movement of the volume control knob A. The mechanical connections and circuit relations are such that the simultaneous movement of the volume control contacts individually effect volume changes which are the same in sense. Specifically, as the contacts S, S1 are moved upwardly from the position indicated, the volume increases, while conversely, if they are moved downwardly from the position shown, the volume decreases. The relative effectiveness of the resistances in changing volume varies for different positions of the contacts to ensure good quality of reproduction and high ratio of signal to tube noises, etc.

As shown in Fig. 2, the resistances R and R1 are disposed in a common housing H.

2. In radio receiving apparatus comprising a radio frequency amplifier having input and output systems, a detector having an input system coupled to said amplifier and an output system coupled to a sound-reproducing device, a multiple volume control unit comprising a resistance in the input system of said amplifier, a resistance in the output system of said amplifier and disposed adjacent said first resistance, common actuating structure for contacts adjustable along said resistances, and a metal plate positioned between said resistances and connected to earth for preventing movement of said structure in control of volume from producing noises in said sound-reproducing device, resulting from rectification by said detector of electrical disturbances incident to variation of said resistances. 15 70
- 20 3. In radio receiving apparatus comprising a radio frequency amplifier having input and output systems, a detector having an input system coupled to said amplifier and an output system coupled to a sound-reproducing device, a multiple volume control unit comprising a resistance in the input system of said amplifier, a resistance in the output system of said amplifier, common actuating structure for contacts adjustable along said resistances, and metal plate structure interposed between said resistances and connected to earth for preventing impression of electrical disturbances incident to adjustment of said second resistance on said first resistance and by rectification of said detector appearing as noise in said sound-reproducing device. 25 80
- 30 4. Radio receiving apparatus comprising a thermionic tube for amplifying radio-frequency signal energy, an adjustable resistance, in the input circuit of said tube for varying the signal voltage impressed on the grid thereof, a resistance for varying a direct-current difference of potential between the cathode of said tube and another electrode thereof disposed adjacent said first resistance, common structure for adjusting said resistances, and conductive plate structure interposed between said resistances and connected to earth. 35 90
- 40 5. Radio receiving apparatus comprising a thermionic tube for amplifying radio-frequency signal energy, an adjustable resistance in the input circuit of said tube for varying the signal voltage impressed on the grid thereof, a resistance in the output system of said tube for varying the signal energy impressed on a subsequent detector circuit, and disposed adjacent said first resistance, common actuating structure for said resistance, and a conductive plate between said resistances connected to earth. 45 100
- 50 6. In radio receiving apparatus comprising a thermionic tube, a multiple-volume control unit comprising adjustable resist- 55 105
- ances connected in different circuits of said tube and positioned adjacent each other, common actuating structure for adjustment of said resistances and a metal plate structure disposed between said resistances and connected to earth. 60 110
7. Radio receiving apparatus comprising a screen-grid tube for amplifying radio-frequency signal energy, an adjustable resistance in the input circuit of said tube for varying the signal voltage impressed on the control-electrode thereof, an adjustable resistance for varying the potential of the screen-grid of said tube and disposed adjacent said first resistance, and conductive structure connected to earth and disposed between said resistances to isolate them electro-magnetically and electro-statically from each other. 75 115
8. Radio receiving apparatus comprising a thermionic tube for amplifying radio-frequency signal energy, radio-frequency transformers in the input and output systems of said tubes, adjustable resistances in shunt to the primary windings of said transformers, a common housing for said resistances, a common actuating shaft for said resistances, and a metal plate within said housing between said resistors and connected to earth. 80 120
9. Radio receiving apparatus comprising a thermionic tube for amplifying radio frequency signal energy, a housing, a grounded metal plate within said housing for dividing it into electro-magnetically and electro-statically isolated compartments, volume control resistances within separate compartments of said housing and included in the input and output systems of said tube respectively, and a common actuating member for effecting concurrent adjustment of said resistances. 90 125
10. Radio receiving apparatus comprising a thermionic tube for amplifying radio-frequency signal energy, a housing, adjustable resistances disposed within said housing and included in the input and output systems of said tube, and a common actuating member for said resistances, at least one of said resistances having a distortable, grounded contact plate for varying it and interposed between the resistances electro-magnetically and electro-statically to isolate them. 100 130
